UNITED STATES PATENT OFFICE.

HENRY K. GILBERT, OF CHICAGO, ILLINOIS, ASSIGNOR TO AMERICAN BRAKE SHOE & FOUNDRY COMPANY, A CORPORATION OF NEW JERSEY.

BRAKE-SHOE.

No. 838,317.

Specification of Letters Patent.

Patented Dec. 11, 1906.

Application filed December 19, 1905. Serial No. 292,421.

To all whom it may concern:

Be it known that I, HENRY K. GILBERT, a citizen of the United States, residing at Chicago, in the State of Illinois, have invented a certain new and useful Improvement in Brake-Shoes, of which the following is a specification.

The invention relates to brake shoes of the type having a back portion of tough reinforcing metal and a body portion secured thereto by casting it about the back portion. The objects of the invention are: to provide a brake shoe of this general type in which the backing piece serves not only as a truss for stiffening and strengthening the body, but also serves as a support for the key lug, and to provide a shoe in which the key lug is made of malleable metal and supported by the back portion and by an extended part of the body portion. The invention is illustrated in the accompanying drawings, in which—

Figure 1 is a plan view;

Figure 2 is a longitudinal section through Figure 4 on the line (2)-(2);

Figure 3 is a similar section through a modified form of shoe;

Figure 4 is a transverse section through Figure 1 on the line (4)-(4); and

Figures 5, 6 and 7, are respectively a plan, end section, and central transverse section of a modified form of shoe.

As shown in the drawings, there are three essential parts to applicant's brake shoe, viz;—the body portion 5, the two longitudinal stiffening back pieces 6 and the part 7 which will be termed the key lug. The parts 6 and 7 are composed of malleable metal such as wrought iron or steel and are secured in their positions by casting the body portion 5 about them. The key lug 7 is preferably a section from a commercial square tube of steel. It is placed at the corner of the shoe and is held in position by an extended portion 8 of the cast body portion which extends over the top of the lug and by a portion 9 of the cast body portion which is inside of the lug. The back pieces 6 as shown consist of strips of wrought metal in cross section of the shape shown in Figure 4. This cross section may be varied, however, and may be square or of some other shape, if desired. These strips 6 are placed flatwise in the body portion of the shoe as shown in Figure 2. At

the right hand end of the shoe the rod is given a twist and turned up so that it passes outside of the body of the shoe, is curved over, passing through the projecting body portion 8 near the corners of the key lug 7 and is turned down at the left hand end adjacent to the starting end, so that the two ends are embedded in the cast metal. This arrangement may be modified as shown in Figure 3, and the two ends may be placed in the upper projecting body portion of the part 8, the essential thing being that the two ends wherever they may be be covered and so firmly held by the cast metal. The two back pieces 6 are spaced far enough apart to avoid interfering with the key which is to pass through the key lug 7. It will be seen that by the above construction a strong key lug of a metal different from the body is secured and that such lug by virtue of the supporting pieces 6 and the engaging portions of the cast metal 8 and 9 is as securely held as if integral with the cast or body portion. The passing of the back pieces 6 through the portion 8 also serves to materially stiffen such projecting portions, especially against a longitudinal blow which might otherwise displace or break the lug. The preferred arrangement of the part 6 is as shown, but it is evident that the strip might be reversed in position and passed through the body of the shoe edgewise instead of flatwise. This modification is comprehended by my invention.

In Figures 5, 6 and 7, still another modification is shown. In this form of shoe a single reinforcing strap 13 is used, which strap passes three times through the cast body of the shoe and twice through the lug. As shown in Figure 5, the truss 14 starts at the right hand end in the body of the shoe, emerges therefrom, passes through the lug 15 and returns into the body of the shoe at the point 16. The strap then crosses to the right hand side of the shoe inside the body thereof, turns and diagonals back to the left hand side in the same plane and then turns again and passes back to the right hand side where it is curved up and emerges from the body of the shoe and forms the truss 17, which truss passes through the lug 15 and enters the body of the shoe at 18. The manner in which the ends of the strap are secured is shown in detail in Figure 6, in which the strap 13 is shown as hooked so as to embrace the adjacent end

of the strap as at 19. It is not necessary that the straps have this hooked engagement, as it is apparent that the straps might end as shown in the left hand end of Figure 2. It is also apparent that in the form of shoe shown in Figure 2 the hooking of the ends of the strap might be accomplished in the same way as is shown in Figure 6. The hooking of the strap of course forms a more secure fastening and prevents the pulling out of the ends of the strap. In Figure 7, which is a cross section at the center of the shoe of Figure 5, the location of the different sections of the strap is clearly indicated, the three lower sections being the section shown in dotted lines in Figure 5.

Having thus described my invention and illustrated its use, what I claim as new, and desire to secure by Letters Patent, is the following:

1. In combination a brake shoe comprising a cast body, a malleable key lug and a malleable back piece adapted to support the body portion and the upper part of the key lug.
2. In combination a brake shoe comprising a cast body, a malleable key lug embraced by the body portion and a malleable back piece embedded longitudinally in the body portion and also in an extended part of the body portion adjacent to the top of the key lug.
3. In combination a brake shoe comprising a cast body, a malleable key lug secured in the body portion at its base and embraced by an extended portion of such body portion and a malleable back piece embedded longitudinally in the main body portion and having an arched portion passing through the extended body portion adjacent to the top of the key lug.
4. In combination a brake shoe comprising a cast body, a malleable key lug secured in the body at its base and embraced by an extended portion of such body and a malleable

back piece of rectangular cross section embedded longitudinally in the main body portion and having an arched portion passing through the extended portion of the body adjacent to the top of the key lug. 45

5. In combination a brake shoe, a cast metal body portion and a lug therefor comprising a section of malleable pipe. 50

6. In combination a brake shoe comprising a cast body portion, a malleable key lug and a pair of malleable back pieces on opposite sides of the body portion adapted to stiffen such body portion and hold the key lug at the top thereof. 55

7. In combination a brake shoe comprising a cast body portion, a malleable key lug, and a pair of malleable back pieces of rectangular cross section embedded in opposite sides of the body portion and extending adjacent the top and bottom of the key lug and adapted to secure such key lug. 60

8. In combination a brake shoe comprising a cast body portion, a malleable key lug embedded in the top of the body portion and having its upper portion surrounded by an extended part of the body portion, and a pair of malleable back pieces embedded on opposite sides of the body portion and arched so as to extend through the extended part of the body portion adjacent to the top of the lug. 70

9. In combination a brake shoe comprising a cast body portion, a malleable key lug, and a pair of malleable back pieces embedded edgewise in the body portion and located on opposite sides thereof and adapted to stiffen such body portion and to engage and secure 80 the upper portion of the key lug. 75

In testimony whereof I have hereunder signed my name in the presence of the two subscribed witnesses.

HENRY K. GILBERT.
